UNITED STATES PATENT OFFICE.

CHARLES WHITING BAKER, OF MONTCLAIR, NEW JERSEY.

GENERATION OF STEAM.

SPECIFICATION forming part of Letters Patent No. 529,997, dated November 27, 1894.

Application filed February 17, 1894. Serial No. 500,536. (No model.)

To all whom it may concern:

Be it known that I, CHARLES WHITING BAKER, a citizen of the United States, residing at Montclair, in the county of Essex and State of New Jersey, have invented certain new and useful Improvements in the Generation of Steam, of which the following is a specification.

The object of my invention is to secure a greater economy than heretofore in the generation of steam, and to effect this result without any radical change in or departure from the ordinary characters or types of generators.

Experiments have shown that the ordinary tubes of generators, both fire-tube and water tube generators, can transmit a far greater proportion of heat from the fire surface to the water surface than is transmitted in any of the ordinary constructions. Various efforts have been made from time to time to utilize a greater proportion of the heat developed in the combustion of the fuel than ordinarily results, as by means for retaining the heated gases in contact with the tubes, by the adoption of tubes of peculiar construction and arranged in various ways and by departures from the ordinary forms of furnaces, but so far with the best instrumentalities employed only a fraction of the heat that should be available is utilized, and many of the means employed have resulted in such increased expense in manufacture or use or in such serious obstruction to the draft, or in rendering the cleaning of the tubes difficult that practically but a very little benefit has ensued while in most cases the means employed could not be used in connection with boilers already constructed, or of ordinary types.

In the course of many experiments it became apparent to me that the greater portion of heat imparted to the tubular heating surface of boilers from the heated gases was received by convection or direct contact of the gases with the tubes and that but a small percentage of the heat from the great body of gases traveling within or passing the tubes, but not in direct contact therewith was conveyed to said tubes and to the water in contact therewith. Taking for an example the case of a locomotive boiler, although the tubes are of very small diameter, two inches

or less, and are usually ten feet or more in length, the gases pass through them so rapidly that they pass into the smoke box and are discharged while still at a temperature far above that of the water in the boiler. The high velocity of the heated gases gives them no time to mix by the process of convection in passing through the tube and consequently while those particles in direct contact with the tube become cooled, the highly heated gases in the central portion of the tube cannot impart heat by contact with the tube except as they are displaced by the comparatively slow process of mixing due to the friction of the gas on the tube.

It has long been known that heated gases have almost no radiating power. Thus the heating surface in the fire box of a locomotive boiler, which is exposed to the direct radiation from the fire, makes many times as much steam per square foot of surface exposed as does the heating surfaces in the tubes, which derive no heat from radiation and are practically heated only by contact with the rapidly moving gases.

In endeavoring to devise means by which the highly heated gases in the central portion of the tube might be made to impart their heat to it, I searched for some method of producing in the tube an equivalent to the radiating action which occurs in the fire box of a locomotive boiler. While engaged in these studies I made the discovery that this could be effected with great simplicity and without detracting at all from the efficiency of those portions of the gases which were in direct contact with the tube surface by immersing in the comparatively non-acting portions of the gases, plates of such a character and so arranged as to radiate the heat thus imparted to them directly to the tube surfaces, and that by this means it was entirely practicable to utilize a large proportion of heat which would otherwise be lost. In order to render this means of economically generating steam available in boilers of ordinary type, I have provided the generators with the said radiating surfaces as fully set forth hereinafter and as illustrated in the accompanying drawings, in which—

Figure 1 is a sectional elevation of a vertical fire tube boiler provided with means for

carrying out my improvement. Fig. 2 is a cross section, enlarged, through one of the tubes, illustrating the arrangement of the radiators. Fig. 3 is a vertical transverse section of a water tube boiler, illustrating one means of carrying out my invention in connection with this class of steam generators.

Whatever may be the construction of the generator in which my improvement is carried out, I arrange within those channels or passages, through which the heated gases or products of combustion must flow from the fire place to the flue, plates of suitable form which I term "radiators" and which are so placed that they will be heated by those gases which do not come in direct contact with the boiler plates and that the heat thereof will be radiated as directly as possible to the surfaces of said boiler plate.

While the radiators may be of different forms and are arranged according to the characters of the generators, I have shown them in Figs. 1 and 2 where the gases pass through the boiler tubes, in the form of tubes arranged concentrically within the said boiler tubes, while in Fig. 3 where the boiler is of the water tube type, I have shown them in the form of curved plates partially surrounding the tubes but with the curves of the radiators concentric with the tubes. In any case there is no obstruction by the radiators *a* to the passage of the products of combustion in direct contact with the tubes or plates of the boiler, but they can thus flow in the same manner and to the same extent as would be the case if the radiators were not employed, while the said radiators become very highly heated and the heat thereof is radiated directly to the surfaces of the tubes through or over which the water passes.

Inasmuch as (as has been found) the boiler tubes normally have a heat but slightly in excess of that of the water in contact therewith while the heat of the radiator will closely approach the maximum heat of the products of combustion the amount of heat radiated from the latter to the former will be such as to very materially increase the heating effect upon the water in the boiler and the amount of water evaporated within a given time.

As the result of numerous experiments I have ascertained that with certain variations, depending upon the character of the generator and the form and arrangement of the radiators an increased efficiency of from twenty to fifty per cent. is readily attainable and wholly practicable.

It will be seen that the radiators *a* may be arranged within the fire tubes or outside the water tubes in boilers of ordinary construction, and already in use, that they do not interfere with the ready cleaning of the boilers or tubes, that they are of a character to be

made and applied at an immaterial expense in proportion to the effect produced, that they 65 in no way interfere with either the circulation of the water or the direct heating action of the products of combustion, and it will be evident that in proportion as they become coated and blackened by carbonaceous deposits their radiating efficiency is increased.

I am aware that deflector plates have been arranged in generators to change the direction of flow of the products of combustion, but any radiation of heat thus secured has 75 been too insignificant to be of practical value and the possibility of a systematic arrangement of such plates or other objects has never been recognized. My invention differs from generators having such deflectors in the systematic arrangement of radiators throughout 80 the generator, substantially in respect to all the tubes, and in the discovery that by such means a great increase of generating efficiency is secured.

I do not here claim the peculiar arrangement of radiators illustrated in Fig. 3, in connection with a water tube boiler as the same constitutes the subject of a separate application for Letters Patent, Serial No. 491,043. 85

Without limiting myself to the use of radiators of special forms and arrangements, I claim as my invention—

1. The within described improvement in increasing the efficiency of steam generators, the same consisting in carrying the heated gases that are not in direct contact with the boiler plates or tubes in contact with plates arranged in proximity to the tubes throughout the generator in position to radiate the heat to said boiler plates or tubes, substantially as set forth.

2. The within described improvement in generating steam the same consisting in passing the gaseous products of combustion in contact with tubes containing or surrounded by the water to be heated, and in radiating the heat of said gases from radiators heated by said gases and arranged adjacent to said tubes throughout the generator, substantially as set forth.

3. The combination with the tubes of a boiler, of radiating plates corresponding in outline with said tubes, and arranged throughout the generator adjacent thereto but out of contact therewith within the fire spaces or channels, substantially as and for the purpose set forth.

In testimony whereof I have signed my name to this specification in the presence of 120 two subscribing witnesses.

CHARLES WHITING BAKER.
